AGITATOR FOR MAINTAINING A THAWED ZONE IN A FROZEN POND

George Doyle Clugston, P.O. Box 581, R.R. 3,
Pittsburg, Kans. 66762

Filed Oct. 10, 1972, Ser. No. 295,897

Term of patent 14 years

Int. Cl. D23—99

U.S. Cl. D23—167

Fig. 1.

Fig. 3.

Fig. 2.

Fig. 4.

Fig. 5.

FIG. 1 is a perspective view of the agitator for maintaining a thawed zone in a frozen pond showing my new design;

FIG. 2 is a side elevational view thereof;

FIG. 3 is a top plan view thereof; and

FIG. 4 is a second embodiment of my design, it being understood that the second embodiment differs from the first only in the substitution of a straight telescoping leg and foot for the original leg and foot; and

FIG. 5 is a top plan view of the second embodiment of my design.

I claim:

The ornamental design for an agitator for maintaining a thawed zone in a frozen pond, substantially as shown and described.
